DOOR STOP

Gustave F. King, Seminole, Okla., assignor of one-half to Forrest D. King, Perry, Okla.

Application November 20, 1950, Serial No. 196,593

3 Claims. (Cl. 292—339)

The present invention relates to door stops, and more particularly, to a device for holding truck or moving van doors open while the vehicle is being loaded or unloaded.

Many conventional enclosed trucks or vans have rear openings occupying the major portion of the rear area of the vehicle body. Such vans usually have two inwardly closing doors which are mounted on vertical axes, and the swinging edges of which meet when closed, so that the doors completely fill or close the opening. Such vehicles have a flat panel which is approximately as wide as the van floor, and which has one end hingedly connected to the rear end of said floor by horizontally disposed hinges. The panel is disposed on end in a vertical position just outside of the closed doors, when the truck is traveling. The free swinging end of the panel may be swung rearwardly downward to form a loading or trucking ramp along which freight may be moved, in loading or unloading the van. The arrangement is such, that the panel may be disposed at various downwardly sloping angles to the truck floor, when freight is to be moved therealong.

With the panel lowered, and with the doors swung open, there is no way at the present time of effectively anchoring the doors in their open positions, with the result that they are at the mercy of the elements, and may be blown shut during freight movement into and out of the van. The doors of the van are normally restricted from blowing full open by chains (not shown) connecting the doors to the ramp.

The principal object of the present invention is to provide a door stop mechanism which will effectively hold the doors open when the ramp panel is in its lowered position.

Another object is to provide a door stop mechanism which is portable, and one of which may be removably anchored to each side edge of the lowered ramp panel, said mechanism having a door stop element rigidly held in the closing path of the swinging door.

A further object is to provide a stop mechanism which is sturdy in construction, and which is simple to install.

An additional object is to provide a device for the purposes set forth, which will not materially interfere with the movement of freight along the ramp.

Other objects will be apparent from the following description when taken in conjunction with the accompanying single sheet of drawings, wherein:

Figure 1 is a perspective view showing a pair of the devices of the present invention operatively installed upon the ramp of a conventional van, the van and ramp being shown in dotted lines;

Figure 2 is a fragmentary perspective view, showing one of the devices operatively installed on the ramp of the van; and,

Figure 3 is a perspective view of one of the devices.

Like characters of reference designate like parts in those figures of the drawings in which they occur.

2

In the drawings:

The reference numeral 1 indicates the rear end of a conventional moving van, having a rear opening 2 adapted to be closed by two laterally swinging doors 3 and 4. 5 The van 1 has a floor 5 to the rear end of which is hingedly mounted one end of a tail-gate 6, which is adapted to be swung downwardly from a normal vertical position behind the doors 3 and 4 when they are in closed positions, to a downwardly sloping rearwardly extending position as shown in Fig. 1. When in such a position, the tail-gate acts as a ramp along which freight may be moved into or out of the van. The ramp 6 may be disposed at various angles with relation to the floor 5.

10 It may readily be seen that with the ramp 6 in its rearwardly extending position, and with the doors 3 and 4 in their open positions, there is a considerable open space between the upper surface of the ramp, and the lower edge of each door.

20 The device of the present invention is designed to be installed upon the ramp to hold one of the doors in its open position, when the ramp is in use. Since the ramp 6 is wider than the door opening 2, and since the ramp may be disposed at various angles with relation to the 25 bottom edges of the two doors 3 and 4, a door stop installed upon the ramp must, in order to be practical, be capable of adjustment to various positions with relation to the upper surface and the side edge of the ramp. With these requirements in mind, the device of the present 30 invention has been designed. It will be further understood that the ramp 6 may be connected as by a chain (not shown) to the doors of the truck to restrict their outward movement.

35 The device, per se, of the present invention includes a flat straight elongated strip 10 of strap-metal, having an integral downwardly turned hook 11 at its outer end. The hook 11 is shaped to envelop the side edge portion of the ramp 6, when the strip 10 is resting flatly upon the upper surface of the ramp, as shown in Figs. 1 and 2.

40 The strip 10 has two spaced apart upwardly projecting parallel ears 12 and 13 which are alignedly perforated transversely to receive a pivot or hinge pin 14. With one of its ends pivotally mounted on the pin 14, there is provided a stop element 15 which is also made of a 45 piece of strap metal.

Intermediate its ends, the stop element 15 is also provided with two parallel ears which are indicated by the reference numerals 22 and 23. The ears 22 and 23 are alignedly perforated transversely to receive a pivot pin 24, which pivotally mounts one end of a strap-metal brace member 25. The free end brace 25 is adapted to slide along the upper surface of the strip 10 as the free end of the stop 15 is moved toward or away from the strip or base 10.

50 55 A stop shoulder 26 is provided between the two ears 12 and 13 to limit outward swinging movement of the stop 15, so that it cannot be moved outwardly beyond a position of perpendicularity to the strip 10.

Intermediate its ends, the upper surface of the strip 60 10 is provided with a plurality of spaced upwardly projecting lugs or deformities 27, 28, and 29, against any selected one of which the free end of the brace 25 may be engaged to hold the stop 15 in various upwardly projecting angles. The utility of these different lugs is 65 illustrated in Figs. 2 and 3 in which the lower end of the brace 25 is illustrated as abutting different ones of the lugs.

70 It is pointed out that one of the devices is positioned upon the ramp for each of the doors 3 and 4, and that when in operative positions, the devices do not interfere with the trucking or carrying freight along the ramp 6. Obviously the invention is susceptible to some change

or alteration without defeating its practicability, and I therefore do not wish to be confined to the preferred embodiment shown in the drawings and described herein, further than I am limited by the scope of the appended claims.

I claim:

1. A door stop for the purposes set forth, including: a flat strip of strap-metal; a downwardly turned hook on one end of the strip; a straight strap-metal stop element having one end hingedly connected to the upper surface 10

of said strip intermediate the ends thereof, said element swingable from a horizontal to a vertical position; a straight strap-metal brace having one of its ends hingedly connected to said stop element, so that the free end of said brace may contact the upper surface of said strip as said element is moved on its hinge; means on the 15

said strip for selectively stopping movement of the said brace in one direction; means for limiting movement of

said element upwardly away from said strip.

2. A stop mechanism for horizontally swinging doors 20

which are located above a vertically tilted ramp, the combination including: a flat elongated base member adapted to lie flatly on said ramp with its forward end beneath the open door and substantially even with one side of the ramp; a downwardly turned hook carried by 25

the forward end of said base member for clasping the edge of said ramp; an elongated strap element having its

lower end hingedly connected to the upper face of said base member and swingable between horizontal and vertical positions; and means for selectively anchoring said stop element in various positions with relation to said base member.

3. In a door stop mechanism for limiting the inward travel of van doors where a ramp is utilized between truck and ground, the combination including: a pair of substantially flat base members each having one U-shaped end for clasping the edges of said ramp on either side and being provided with a series of outwardly facing notches on the upper face thereof; pivotal means on the upper face of each said base member proximate the said U-shaped ends thereof; and elongated stop members hingedly connected to each of said pivotal means; and a brace hingedly connected to said stop members intermediate the ends thereof and adjustably engageable in the notches of said bases to vary the position of said stop members between the horizontal and vertical.
